UNITED STATES PATENT OFFICE.

LINDSAY L. HILL, OF LOUISVILLE, KENTUCKY.

RAILROAD-CROSSING GATE.

1,226,213.

Specification of Letters Patent.

Patented May 15, 1917.

Application filed March 7, 1916. Serial No. 82,719.

To all whom it may concern:

Be it known that I, LINDSAY L. HILL, a citizen of the United States, residing at Louisville, in the county of Jefferson and State of Kentucky, have invented certain new and useful Improvements in Railroad-Crossing Gates, of which the following is a specification.

My invention relates to new and useful improvements in gates for railway crossings, the primary object of my invention being the provision of a railway crossing gate, the barriers of which may be raised or lowered with the greatest possible rapidity.

A still further object of my invention is to provide a gate mechanism and operating structure therefor of such a character that a railway gate embodying two coacting road guarding barriers and sidewalk guarding barriers may be actuated by a single hand lever, all of the barriers being raised or lowered simultaneously.

A still further object of my invention consists in the provision of a novel form of lever and link mechanism co-acting between each road guarding barrier and sidewalk guarding barrier, whereby actuation of the road guarding barrier will cause corresponding movement of the other barrier.

In this connection, a still further object of my invention consists in so proportioning the links, levers and other parts of the operating mechanism that a relatively small angular movement of the hand lever is all that is necessary to fully raise or lower the gate.

As will be apparent after a more complete understanding of my invention, a still further object consists in the provision of a railway gate structure in which the cost both of installation and maintenance is reduced. To accomplish this, I necessarily provide a gate structure and operating mechanism of unusual simplicity.

With these and other objects in view, my invention will be more fully described, illustrated in the accompanying drawings, and then specifically pointed out in the claims which are attached to and form a part of this application.

In the drawings:

Figures 1 and 1^a are perspective views, showing the invention complete;

Fig. 2 is a front elevation, partially in section, showing my improved railway crossing gate in lowered position;

Fig. 3 is a vertical sectional view taken on the line 3—3 of Fig. 2;

Fig. 4 is a vertical sectional view taken on the line 4—4 of Fig. 3.

Corresponding and like parts are referred to in the following description and indicated in all the views of the drawings by the same reference characters.

In the preferred embodiment of my invention, I provide supporting bases 10, one at either side of the road, preferably between the sides of the road and adjacent sides of the sidewalks, in the form of piers or abutments constructed of concrete, masonry or other material. Each of these piers supports a standard, indicated as a whole by the numeral 11, and each standard carries a road guarding barrier 12 and sidewalk 70 guarding barrier 13.

More specifically, each standard 11 is substantially U-shaped and provided at its free ends with laterally directed feet 14 which rest upon the bases 10 to which they are secured by bolts 15 or other suitable fastening means passed through the feet and anchored in the concrete of the base. Each of these standards, adjacent its upper end, has its sides formed with aligned openings 85 16 to receive a bearing sleeve 17. This sleeve forms a cage for a plurality of roller bearings 18 which in turn journal the pivot bolt 19 upon which the main or road guarding barrier 12 is mounted. In like manner and in spaced relation above this sleeve is located a second bearing sleeve 20 which forms a race for roller bearings 21 which journal the pivot bolt 22 of the sidewalk guarding barrier 13. The barrier 13 includes the barrier bar proper 23, which is preferably constructed of wood and which is secured at one end between the ends of the side members 24 of the barrier head 25 by bolts 26 or other suitable fastening 100 means. These side members of the barrier head 25 seat between the flanges of channel metal frame plates 27 which engage one at either side of the standard 11 and the members 24 may be secured in these plates 105 by any suitable fastening means. The inner faces of the members 24 are recessed, as shown at 28 in Fig. 3 of the drawings, to

seat the head of the pivot bolt 22 and the nut 29 which holds the bolt in place.

In like manner, each barrier 12 includes a barrier bar proper 30 which is secured at one end by bolts or other fastening means 31 between the insprung ends of the side bars 32 of the barrier head 33, the barrier proper 30 and side bars 32 being preferably formed of wood. The side bars 32, at their other ends, seat between the flanges of channel plates 34, corresponding to the channel plates 27 and are secured in such plates by bolts 35 or other suitable fastening devices. These channel plates 34, intermediate their length, are formed upon their inner faces with inwardly directed bosses or hubs 36 which engage the outer sides of the standard 11 and serve to space the plates 34 outwardly a sufficient distance 10 to give them clearance and permit them to swing past the outer sides of the barrier head 25 during movement of the gate, as will be later apparent. The inner faces of the side bars 32 are recessed, as shown at 15 37 in Fig. 3, to seat the head of the pivot bolt 19 and the nut 38 by means of which such bolt is held against displacement. Preferably, the side bars 32 are braced and secured in proper spaced relation by one or 20 more spacer members 39 and in like manner the side plates 27 are braced and spaced by a spacer bolt 40.

The operating mechanism for the barriers at one side of the road is identical with that of the barriers at the other side and a description of one will suffice for both. Each mechanism includes a bell crank lever 41 which is pivotally supported between the side members of the standard 11 by a pivot bolt 42, that portion of the lever through which the pivot bolt passes being formed with bearing hubs 43, as best shown in Fig. 3. Double links 44 pivotally connect the laterally directed arm of the lever 41 with the free end of the barrier head 33, a pivot bolt 45 being passed through the sides of the barrier head and the ends of the links 44. This pivot bolt 45 not only serves as a means for connecting the links 44 to the 45 barrier head, but also carries a plurality of counterweights 46, preferably of such a type that their combined weight may be readily adjusted by some well known means, such as the addition or removal of shot from a chamber contained in one of them. At this point it should be noted that these counterweights are intended not only to counterbalance the main or road guarding barrier 12 and its operating mechanism, but also the 50 supplemental or sidewalk guarding barrier 13. A second bell crank lever 47 is pivotally supported between the sides of the standard 11 and in spaced relation above the lever 41 by a pivot bolt 48 passed through 55 the sides of the standard and through

the hub bearings 49 of the lever, double links 50 pivotally connecting one arm of this bell crank lever 47 with the intermediate portion of one arm of the lever 41 and a link 51 correspondingly connecting the other arm 70 of the bell crank lever 47 with the intermediate portion of the barrier head 13. Preferably, the spacer bolt 40, previously mentioned, is employed for this latter connection. 75

At this point it should be noted that the bell crank levers 41 and 47 are reversely disposed so that a downward swinging movement of the lateral arm of the lever 41, which is the movement required to raise the 80 barrier 12, will result in a downward swinging movement of the lateral arm of the lever 47, which is necessary to raise the barrier 13.

The bases or piers 10 are preferably partially embedded in the earth, as best shown in Figs. 1 and 2, and disposed in spaced relation to these piers are additional piers 52 which are correspondingly embedded in the earth. Of course, the piers 10 and 52 90 may be constructed as one, if desired. Each of the piers 52 is formed with a chamber 53 opening through its upper face and a lever 54 is pivotally supported at its lower end in the lower end of one of these chambers by a pivot bolt or rod 55, the ends of which are preferably embedded in the concrete or masonry of the structure. A corresponding lever 56 is pivoted intermediate its length in the chamber of the pier 52 100 by a pivot bolt 57 and the downwardly extending portions of these levers are pivotally connected to the depending arms of the bell crank levers 41 by links 58. A pipe or conduit of tiles or other suitable material 59 extends from one of the piers 52 to the other and serves as a housing for a connecting rod 60 which is pivoted at its ends to the intermediate portion of the lever 54 105 and to the inner or lower end of the lever 56, as clearly shown in Fig. 2. Preferably, rollers 61 are projected transversely across the lower portion of the pipe 59 at suitable intervals to support the connecting rod 60 and thus reduce the force required to 110 move it.

From the foregoing description, it will be apparent that a swinging of the upper end of the lever 54 toward the standard 11 will not only cause a raising of the gate 120 barriers 12 and 13 supported by that standard adjacent the lever 54, but will also act through the connecting rod 60 and mechanism at the other standard 11 to raise the barriers carried by the other standard. 125

As previously stated, one of the objects of this invention is the provision of a mechanism by means of which the gates may be operated from any convenient point, such as a watch tower or signal station. Such 130

a mechanism is shown in Fig. 1^a in which suitable piers or abutments 62 pivotally support oppositely disposed bell crank levers 63 and 64 which have their parallel arms pivotally connected by a link 65. A link 66 pivotally connects the other arm of the bell crank lever 63 with the upper terminal of the lever 54, while a link 67 pivotally connects the free arm of the bell crank lever 64 with one arm of a vertically disposed bell crank lever 68 carried by a pier or abutment 69 disposed below the watch tower or signal station, not shown. A link 70 pivotally connects the free arm of the bell crank lever 68 with the laterally directed arm 71 of a vertically swinging hand lever 72 of the bell crank type. The handle arm of this lever is swingingly mounted between parallel toothed sectors 73 and is provided with a spring pressed hand latch mechanism 74 by means of which it may be locked in any desired position.

In order to keep the chambers or recesses in the piers 52 free of dirt and leaves, which would in time work into the pipe 59 and interfere with the operation of the gate, I provide sliding closure plates 75 which are free for movement over the top of the pier and which are formed with small openings 30 to receive the projecting ends of the levers 54 and 56. These plates are, of course, so proportioned that in all positions of the levers projecting through them, they completely close the chambers. As a rule, the various levers and links leading from the lever 54 to the link 70 will be inclosed in a suitable housing either below the surface of the ground or directly upon the ground, but I have not shown such housing as it would interfere with the proper disclosure of the mechanism itself. Any suitable type of hook 76 may be attached to the main barriers 12 to support a lantern or other signal device.

Preferably, the links 51 and 58 and the link 66 are made adjustable in the manner shown, in order that the operating mechanism may be adjusted with nicety and any loose play, due to wearing of the parts, taken up from time to time. For the same reason, turn buckles 77 are employed to connect the ends of the connecting rods 60 to the levers 54 and 56, these turn buckles being so disposed that they may be adjusted from the chambers 53 of the piers 52. Also one or more turn buckles 78 may be included in the various links leading from the gate mechanism to the operating lever 72.

It will of course be apparent that numerous minor changes in construction may be made without in any way affecting the principles of operation of my crossing gate and its operating mechanism and I therefore reserve the right to make any changes 65 within the scope of the appended claims.

Having thus described the invention, what is claimed as new is:

1. A gate for railway crossings including standards adapted to be positioned at opposite sides of a roadway, oppositely extending barriers swingingly mounted upon each standard, connecting means between the barriers of each standard, whereby movement of one will cause corresponding movement of the other, a bell crank lever on each standard connected to a barrier thereon, a lever pivoted adjacent one end near one standard, a lever pivoted intermediate its length adjacent the other standard, links connecting the free ends of the levers with the free ends of the bell crank levers, a connecting rod connecting the intermediate portion of the first lever with the free end of the second lever, and means for swinging one of the levers. 85

2. In a railway crossing gate, a standard adapted to be located adjacent the crossing and including spaced sides, a main barrier swingingly supported adjacent one end upon the standard, a supplemental oppositely extending barrier pivotally supported at one end upon the standard, bell crank levers pivotally supported upon the standard with one arm of one lever projecting in the opposite direction to the corresponding arm of the other and with their remaining arms extending parallel, a link connecting the free end of the parallel arm of one bell crank lever with the intermediate portion of the corresponding arm of the other, a link connecting the free end of the last arm of the bell crank lever with the free end of the main barrier, and a link connecting the free arm of the first bell crank lever with the intermediate portion of the supplemental barrier. 100

3. In a gate construction for railway crossings, a standard, main and supplemental barriers swingingly supported on the standard, bell crank levers swingingly supported on the standard, links connecting certain arms of the bell crank levers with the barriers, and a link connecting the free arm of one bell crank lever with the intermediate portion of that arm of the other bell crank lever which is connected to one of the barriers and means for swinging one of the bell crank levers. 115

4. In a gate construction for railway crossings, a standard adapted to be positioned adjacent a crossing and including spaced side members formed intermediate their height with aligned openings, a sleeve seating at its ends in the openings, a barrier including a head having side portions projecting past the sides of the standard, a pivot bolt passed through the side portions of the barrier head and through the sleeve, and a plurality of roller bearings located in the sleeve and surrounding the pivot bolt 130

and held against displacement by the side portions of the head of the barrier.

5. A gate for railway crossings including a standard, oppositely extending barriers 5 swingingly mounted upon the standard one above the other, bell crank levers swingingly mounted upon the standard, links connect-

ing one arm of each bell crank lever with the barriers, means connecting the free arm of one bell crank lever with the other bell 10 crank lever, and means for operating said latter bell crank lever.

In testimony whereof I affix my signature.

LINDSAY L. HILL. [L. S.]
